CLAIM

(51) **LOC (15) Cl.** **08-05**

The ornamental design for an electric hammer as shown and described.

(52) **U.S. Cl.**

USPC **D8/61**

DESCRIPTION

(58) **Field of Classification Search**

USPC D8/61, 67-704
CPC B25C 1/041; B25C 5/16; B25C 1/003;
B25C 1/005; B25C 1/001; B25C 5/0228

See application file for complete search history.
